John E. Hubbard
ATTORNEY

UNITED STATES PATENT OFFICE

HARRY EDGAR FEAR, OF LAKWOOD, OHIO, ASSIGNOR TO NEW CASTLE REFRactories COMPANY, OF NEW CASTLE, PENNSYLVANIA, A CORPORATION OF DELAWARE

KILN CAR SUPERSTRUCTURE

Application filed November 19, 1929. Serial No. 408,188.

The present invention relates to the construction of trucks or cars for conveying material through a continuous tunnel kiln of the muffle heated type and particularly a kiln of the well known Dressler type in which the kiln chamber is heated by internal combustion chambers and the transfer of heat from the combustion chambers to the material on the cars is primarily by means of convection currents of the kiln atmosphere. More particularly my invention relates to kiln car superstructure constructions comprising a permanent combination of posts and slabs arranged to form a plurality of superposed decks.

In kiln cars of the deck and post superstructure type, it has been the practice in burning flat ware to support the pieces on ware supporting pins mounted in closely spaced deck supporting posts, as is disclosed, for example, in the prior patent of George D. Morris, 1,674,836, granted June 26, 1928. While such a construction has proved efficient for that type of ware, it is not adapted for use in kilns where the ware pieces are of such various sizes and forms as to prevent them from being supported on pins mounted in the posts. The pins have consequently been omitted and the ware pieces supported directly on the decks. The last mentioned arrangement is disadvantageous in that only a small portion of the car capacity is utilized and when the ware pieces are small, the concentration of the ware in one section tends to deflect the circulating atmosphere through the unobstructed portions of the deck passages with consequent lack of uniformity in the heating effect.

The general object of my present invention is to provide a kiln car superstructure of the deck and post type which can be used with a high percentage of its capacity regardless of the size and shape of the ware pieces to be heat treated. In carrying out the object of my invention I provide one or more auxiliary ware supporting decks extending horizontally intermediate the superposed decks. While the auxiliary decks can be permanently arranged at different levels in different portions of the car, I have found it

advantageous to have the auxiliary decks removably mounted in the permanent superstructure, whereby the loading and unloading operations are facilitated and the auxiliary decks positioned at a level corresponding to the height of the ware to be supported thereon.

The various features of novelty which characterize my invention are pointed out with particularity in the claims annexed to and forming a part of this specification. For a better understanding of the invention, however, and the advantages possessed by it reference should be had to the accompanying drawing and descriptive matter in which I have illustrated and described a preferred embodiment of the invention.

Of the drawing:

Fig. 1 is a side elevation of a kiln car incorporating my improved superstructure construction;

Fig. 2 is a perspective view of one of the supporting posts; and

Fig. 3 is a rear elevation of a portion of the car with one of the rear posts removed.

In the construction illustrated, A represents the refractory body portion of a truck or car such as is commonly employed in transporting ceramic ware pieces in continuous tunnel kilns. The body portion is provided with depending bearing members A' in which wheels A² are rotatably mounted. A plurality of transverse I-beams B of one-piece refractory material are arranged on the body portion to form supports for the ware supporting superstructure. The I-beams are spaced apart longitudinally of the car to provide a series of transverse channels C through which the kiln chamber atmosphere circulates.

The car superstructure comprises a permanent portion having a lower deck consisting of a plurality of flat refractory slabs D rectangular in outline and having their adjacent end portions supported on the I-beams B. A plurality of vertical posts E and F are positioned on the lower deck at points spaced longitudinally and transversely of the car, the posts E being arranged intermediate and the posts F at the front and rear edges of

the deck D. A second deck consisting of a plurality of rectangular refractory slabs G is supported on the posts E and F. The superstructure space between the superposed decks 5 D and G is usually connected to the transverse channels C by openings formed in the lower deck along the longitudinal center line of the car, whereby a flow path for the circulating kiln atmosphere is provided.

10 Heretofore in post and deck superstructure constructions, it has been customary to closely space the supporting posts so that the ware is directly supported thereon by ware supporting pins. When, however, the ware 15 is so dimensioned that the use of ware supporting pins is not practicable, the ware pieces are placed on the lower deck D. When the ware pieces are small, it will be readily apparent that only a small portion of the 20 cross-sectional area of the kiln circulating passages is being utilized and also that the kiln atmosphere tends to flow through the unrestricted portions of the passages rather than the occupied portions with consequent 25 inefficient heating of the ware pieces.

To utilize substantially the maximum capacity of the circulation passages of the car superstructure and to bring the kiln atmosphere into more intimate contact with the 30 ware positioned therein, I have provided the posts E and F with means for supporting one or more auxiliary decks intermediate the main decks D and G. In the present construction as illustrated in Figs. 1 and 3 the 35 posts are of rectangular horizontal and vertical cross section and formed with one or more kerfs or notches E' or F' at different levels in their sides extending transversely of the car. The intermediate posts E are formed 40 with notches E' in each transverse side while the posts F have notches F' at their inner sides only. Each of the auxiliary decks consists of one or more thin refractory slabs J of 45 rectangular outline and arranged with their transverse edge portions mounted in corresponding notches E' and F' of adjacent posts E and F, respectively. Preferably, as illustrated in Fig. 3, each auxiliary deck slab is 50 supported by four posts.

Obviously, the number of auxiliary decks used and the levels at which they are positioned depends on the dimensions of the ware pieces to be burned. For example, in Figs. 55 1 and 3 auxiliary decks J are shown positioned in the various notches E' and F' depending on whether the ware pieces R, S or T are to be positioned thereon. The ware pieces positioned in the various superstructure sections may be all of the same dimensions, or pieces of different dimensions combined, whichever arrangement is most efficient.

The slideable mounting of auxiliary decks is advantageous in that these decks may be removed and loaded at the loading benches

and the loaded slab slid into position. This arrangement particularly facilitates the loading and unloading of ware pieces positioned near the center of the car superstructure and permits easy repairs and replacements. 70 These advantages could not be obtained in a construction in which the auxiliary decks are eliminated and the permanent decks spaced vertically a short distance. All of the superstructure members are interchangeable in 75 practice with similar parts.

While I have described the car superstructure with only a single covered deck, it is customary and advantageous to utilize more than one deck. For that reason an upper series of 80 auxiliary deck supporting posts E and F are positioned on the deck G, preferably in vertical alignment with the lower series of posts. A top deck composed of a plurality of refractory slabs H is supported on the upper 85 posts. The deck slabs H are similar to the slabs G and D and their flat upper surfaces may be utilized for supporting ware pieces W of such dimensions as to render positioning them in the lower superstructure passages 90 impractical.

While in accordance with the provisions of the statutes, I have illustrated and described the best form of embodiment of my invention now known to me, it will be apparent to those skilled in the art that changes may be made in the form of the parts disclosed without departing from the spirit of my invention as set forth in the appended claims and that in some cases certain features of my invention may be used to advantage without a corresponding use of other features. 95

Having now described my invention what I claim as new and desire to secure by Letters Patent, is:

1. In a kiln car, a ware supporting superstructure comprising a permanently positioned section consisting of a pair of spaced ware supporting decks formed by horizontally arranged refractory slabs and a series of vertical refractory posts positioned at spaced points on the lower of said decks and arranged to support the upper of said decks, whereby the space between said decks is openly exposed to the kiln atmosphere on all sides, and means for supporting ware pieces of various dimensions in the spaces between said decks consisting of horizontal notches formed in the sides of said posts at various levels therein and interchangeable auxiliary refractory shelves horizontally slideable in corresponding notches of adjacent posts at levels varying with the dimensions of the ware directly supported thereon. 110

2. In a kiln car, a ware supporting superstructure comprising a permanently positioned section consisting of a pair of spaced ware supporting decks formed by horizontally arranged refractory slabs and a series of vertical refractory posts positioned at 115 120 125 130

spaced points on the lower of said decks and arranged to support the upper of said decks, whereby the space between said decks is openly exposed to the kiln atmosphere on all sides,
5 and means for supporting ware pieces of various dimensions in the spaces between said decks consisting of shelf receiving means in the sides of said posts at various levels therein and interchangeable auxiliary refractory
10 shelves horizontally slideable on and relative to said posts at levels varying with the dimensions of the ware pieces directly supported thereon.

Signed at Cleveland in the county of Cuyahoga and State of Ohio, this 15th day of November, A. D. 1929.
